UNITED STATES PATENT OFFICE.

JULIUS SKVARENINA, OF CHICAGO, ILLINOIS, ASSIGNOR TO PETER FLASKA, GUSTAV SOJAK, JOHN FLASKA, AND JULIUS SKVARENINA, IN TRUST FOR THE PARTNERSHIP KNOWN AS THE AMERICAN BENT WOOD CHAIR COMPANY, OF CHICAGO, ILLINOIS.

DESIGN FOR BENT-WOOD CHAIR.

Application filed June 5, 1924. Serial No. 9,800. Term of patent 14 years.

To all whom it may concern:

Be it known that I, JULIUS SKVARENINA, a citizen of the United States, residing in Chicago, county of Cook, and State of Illinois, have invented a new, original, and ornamental Design for Bent-Wood Chair, of which the following is a specification, reference being had to the accompanying drawing, forming part thereof, in which—

Fig. 1 is rear elevational view of the complete chair and Fig. 2 is a side elevational view. These figures illustrate my new design.

I claim:

The ornamental design for bent wood chair, as shown.

JULIUS SKVARENINA.
